ARTIFICIAL FOOT

Edward P. Carmichael, La Mesa, and Charles W. Radcliffe, Albany, Calif., assignors to Consolidated Vultee Aircraft Corporation, San Diego, Calif., a corporation of Delaware

Application September 23, 1947, Serial No. 775,686

17 Claims. (Cl. 3-5)

1

The present invention relates to improvements in artificial limbs and more particularly to a novel construction for an artificial foot.

Conventional artificial feet are ordinarily constructed of one of three types of material: wood (usually willow), felt or vulcanized rubber. Feet so constructed, though having many desirable features, are yet characterized by their being relatively heavy and costly. Such conventional materials as are employed require a method of fabrication which does not lend itself readily to mass production but rather there is demanded relatively skilled personnel to effect the desired contour and exterior appearance. A construction for a foot is contemplated by this invention utilizing light-weight materials which renders the finished product light in weight and relatively inexpensive to manufacture and which foot would adequately meet all the requirements of a satisfactory and dependable foot prosthesis.

It is therefore an object of this invention to provide a foot prosthesis of improved construction which is light in weight, has high impact strength and which has the further advantage of durability.

Another object of the invention lies in the provision of a natural appearing foot prosthesis of improved construction utilizing materials in the composition thereof having a high strength-to-weight ratio and which materials are easily worked.

A further object resides in providing a novel construction for an artificial foot, the parts whereof are readily fabricated and in sizes to fit the needs of the individual amputee and which parts are combined in a manner designed to take full advantage of their desirable characteristics.

A still further object of the invention is the provision of an improved form of artificial foot which has simplicity of construction, is inexpensive to manufacture, and which may be worn by the amputee with comfort.

Other objects and features of the invention will be readily apparent to those skilled in the art from the following specification and appended drawings illustrating certain preferred embodiments of the invention in which:

Figure 1 illustrates a sectional view of an artificial foot constructed in accordance with the present invention;

Figure 2 is a sectional view of the foot taken along line II-II of Figure 1 and for clarity and simplicity showing the ankle joint assembly in dotted outline only;

Figure 3 is a sectional view, enlarged, taken along line III-III of Figure 1; and

2

Figure 4 is a top plan view of the artificial foot of the present invention, again for clarity showing the ankle joint assembly in dotted outline.

Referring now in detail to the drawings, there is shown illustrated an artificial leg indicated generally at 10, embodying a shank 11, only the lower portion of which is illustrated, and a foot prosthesis 12, connected together for common operation by an ankle joint assembly 13. The specific construction of the shank 11 forms no part of the present invention, it being understood that the foot 12 is adapted for use with any variety of shank to which it may be connected as by an articulated joint. The shank 11 illustrated herein is therefore but one form suitable for use with the foot 12 of the present invention. Shank 11, as shown, comprises a centrally disposed, weight-bearing, tubular column 14 about which is positioned a covering or fairing 16 suitably constructed in simulation of a human leg. The tubular column 14 and the covering or fairing 16 may be comprised of any suitable light-weight material.

The foot prosthesis 12 utilizes balsa wood as the basic material of which the primary structure of the foot is comprised. By employing balsa wood in the construction of artificial foot 12 a unit is effected which is much lighter in weight than conventional artificial feet while yet possessing sufficient strength and durability for the purposes required of it. Balsa wood alone however does not possess the requisite surface hardness but it has been found that applying a covering of a synthetic thermosetting resin impregnated laminate thereon the resistance of the basic material, balsa wood, to compressive and impact loads was increased to the desired point. The resin impregnated laminate preferred for use herein is a fibrous glass cloth impregnated with a modified phenolic resin.

The artificial foot 12 is comprised of two major components, a forefoot or toe section 17 and a primary weight bearing section 18. The latter section 18 comprises a basic structure or core 20 consisting of three primary load bearing members or blocks of balsa wood, properly oriented relative to one another for maximum strength. These three primary load bearing members comprise a sole 21 of elongated form, an instep 22, and a heel 23, the instep 22 and heel 23 being secured to the flat top surface of sole 21. A layer 24 of a resin impregnated material, of the type mentioned hereinbefore, is applied to the top surface of sole 21 and serves to bond the instep 22 and heel 23 thereto. This layer 24 incidentally

adds strength to the assembly. The load to be applied to instep 22 and heel 23 will be applied from shank 11. During rotative movement of shank 11, as will be described further, this load will be applied to the upper surfaces 25 and 26 of instep 22 and heel 23 respectively which are engageable by a portion of shank 11. It has been found that balsa wood can sustain compression loads in a much greater degree when such loads are applied parallel to the grain, therefore the grain of both the instep 22 and heel 23, as is shown in Figure 1, run in a vertical direction which is indicated by double-headed arrows. In the case of the sole 21 however the grain thereof runs in a horizontal direction, as indicated by a horizontal double-headed arrow. The sole 21 in effect acts as a beam which is subjected to distributed compression and bending loads.

Assembling together of the sole 21, instep 22 and heel 23, as stated, effects the primary weight bearing core 20 for the foot. It is noted that in external appearance the contour of the core only roughly simulates a foot. To obtain the desired shape and appearance of a normal foot it is necessary to add to this core 20 certain fairings of appropriate configuration, therefore, at either side of core 20, fairings 27 are applied which extend from the bottom surface of the sole 21 to the top surface of the instep 22 and heel 23. These fairings 27 are pre-shaped and when joined to core 20 a normal appearing foot is effected. Fairings 27 are connected to core 20 through the use of bonding layers 28 of resin impregnated material, of similar composition to layer 24, and by the use of reinforcing bolts 31.

The toe section 17 provided forward of core 20 may be formed of one block of balsa wood or may preferably be built up, as in the present invention, of a core portion 32 to which are bonded side fairings 33 and 34, which fairings complete the simulation of a human forefoot. The toe section 17 is adapted to move relative to core 20. In order that an easy, graceful and a natural appearing gait be attained, the motion of toe section 17 must be suited to the amputee's style of walking. To secure the desired movement the toe section 17 is, therefore, not applied or connected to core 20 until the foot is completely contoured and after a fitting is had by the amputee.

In many conventional foot constructions the toe section after a period of use tends to assume a permanent set, which condition decreases the available angle of bend and produces an unnatural appearance in the gait. The toe hinge of the present invention here prevent the occurrence of this fault. The present toe hinge will withstand the repeated flexings to which it will be subjected without breaking down and will yet provide the amount of resistance to bending necessary to the attaining of a natural walk.

The hinge for the toe section 17 is provided by a layer 35 of a sandwich construction comprising sheets of a resin impregnated material disposed on each side of a central layer of rubber. The resin impregnated material utilized is preferably of the same composition as layers 24 and 28 used in bonding together the various blocks of balsa wood comprising core 20. This layer 35 is adapted to serve as more than a hinge for the toe section 17 as it is preferably of sufficient length and breadth to cover the entire bottom of the toe section 17 and of the sole 21. Bonding of the layer 35 over this large area will have the effect of adding strength to the sole and toe members 21 and 17 and will prevent possible failure 75

of the balsa wood in horizontal shear. Further the bottom of foot 12 will be better able to withstand sharp impact blows and shock.

In addition to strengthening the bottom of foot 12 provision is made for further strengthening of the foot as a whole by the utilization of further resin impregnated layers. Thus, over the upper surface of the toe section 17 there is fitted a layer 41 which is bonded to and covers the core 32 thereof and the two side fairings 33 and 34 associated therewith. Another layer 42 is applied over the instep 22, side fairings 27 and heel 23 so that core 20 comprised of these elements is substantially fully encased in a covering having high strength and resistance to shock and sharp impact blows. The layers 24 and 28 used in the bonding together of fairings 27, instep 22, heel 23, and sole 21 also act as reinforcing members for the foot to add to the overall strength thereof.

To prevent the toe section 17 from assuming a reverse bend there is provided a length of cloth 43 made of a strong material, preferably nylon, which bridges a gap 44, of generally triangular or wedge shape, located between the forefoot 17 and core 20, as best seen in Figure 1. The length of cloth 43, best illustrated in Figure 4, is applied to the upper surfaces of the toe section 17 and instep 22, being bonded to the reinforcing layers 41 and 42 carried thereon. With cloth 43 in place it is apparent that the toe 17 cannot bend in reverse direction beyond the plane of the sole.

As illustrated in Figure 1 there is disposed within gap 44 a generally wedge shaped member 45 made of rubber, or a material having similar characteristics, which will determine the amount of clockwise movement of toe section 17. The size of member 45 is determined at the time that a fitting is had by the amputee and his manner of walking noted. By trial the correct size is readily arrived at. This wedge member 45 also acts both as a cushion and as a restoring force for the toe 17. With the construction hereinbefore described a toe action substantially similar to that of a normal foot will be attained.

Bolted to the tubular element 14 at its lower end is a stop member 46, having a flared out portion, as shown, which member 46 moves with the shank 11 as it rotates in clockwise and counterclockwise direction, as viewed in Figure 1, in the act of walking. The amount of rotative movement of shank 11 is determined by a pair of rubber blocks 47 and 48 located on either side of an ankle cavity 51 provided in foot 12. The first block 47 is mounted on the top surface 25 of instep 22 and the other block 48 is secured to the top surface 48 of heel 23. Block 48 will rarely, if ever, be engaged by stop member 46, engagement occurring only when the artificial leg accidentally distorts. But block 48 is provided nevertheless to determine the extent of such accidental backward movement so that it not become too large and injure the ankle connection between the shank 11 and the foot 12.

In normal walking the shank 11 rotates toward and away from the toe section 17 and the block 47 will be constantly engaged and disengaged by stop member 46, carried by shank 11, as strides are taken by the amputee. The height of this rubber block 47 determines the amount of movement, counterclockwise, that may be had by shank 11 relative to foot 12. The individual requirements of a wearer are readily determined by fittings and a block of suitable height is easily arrived at. A readily removable stud 52

mounts the block 47 to the top of instep 22 and it is a simple matter to effect a change in blocks. Block 47 is made of relatively hard rubber but with sufficient give to it that it absorbs and cushions the shock of engagement by stop member 46 and serves to make the to-and-fro movement of shank 11 an even one.

The ankle cavity 51 provided in foot 12 is formed or defined by the fairings 27, the sole 21, instep 22 and heel 23. This cavity or well 51 is adapted to receive the ankle joint assembly 13. As in the case of the shank 11 the particular construction of the ankle joint assembly 13 is not the subject of the present invention and it is to be understood that assembly 13 is to be considered as illustrative of but one form of connector that may be used. The ankle joint assembly 13 does however constitute the subject matter of an application for patent filed July 26, 1947, Serial No. 763,924, which issued into Patent No. 2,450,728 on October 4, 1948, in the name of Glenn G. Havens. For the purpose of this invention, then, the ankle joint assembly 13 will be described but briefly. As is shown in the drawings, ankle joint assembly 13 comprises a tubular connector 61 which fits over the lower end of columnar member 14. The tubular connector 61, as best seen in Figures 1 and 2, necks down into an elongated, flat-sided, depending portion 62, the lower end 63 of which is generally arcuate in configuration. A pair of resilient links or connecting elements 64 and 65 are carried by portion 62 and are disposed one on each side thereof. These links 64 and 65 are respectively secured to mounting plates 66 and 67 which mounting plates are disposed in cavity 51 to effect the connection of shank 11 to foot 12.

The cavity 51 is lined with laminates of the same resin impregnated material that comprises layer 24 which bonds the instep 22 and heel 23 to sole 21. A layer 71 as shown in Figure 1 covers two walls and the bottom of the cavity 51. The lining for the other two walls is provided by the layers 28 which bond the side fairings 27 to core 20.

The mounting plates 66 and 67 disposed in well 51 are secured to the liners 28 by being bonded thereto and further by fasteners 68 and spacer pins 69. The described manner of securing plates 66 and 67 prevents their being torn out of position by anything but a very extreme force.

As a further protection against sharp impact blows there is provided over the foot 12 a cosmetic covering 72 made of rubber and which is slipped over the foot in the same manner that a stocking is. This covering 72, it is obvious, is not a part of the foot construction and may or may not be employed by the wearer.

For best results the balsa wood utilized in the construction of the various parts of the foot 12 of this invention should be of a heavy grade. The physical properties of balsa wood are linearly dependent on its specific gravity and it has been found that balsa woods having specific gravities of about 0.20 and above are to be preferred in the construction of a foot having the desired strength and durability. It is, of course, understood that certain selectivity must be shown in choosing the balsa wood to be worked. The balsa wood used must be free of checks, cracks or other irregularities that may be detrimental to physical characteristics and the grain should be parallel to its greatest dimension. Experience in choosing

suitable balsa wood is readily acquired by the workman.

If desired, the balsa wood parts may be strengthened by impregnation thereof with a suitable synthetic thermosetting phenolic resin and thereafter suitably cured in an oven. Shear strength and compression strength are increased by impregnation though at the cost of a slight increase in weight. However, the present invention is not to be confined to the use of treated or untreated balsa wood for satisfactory foot prosthesis are obtainable with either.

The foot construction described herein is well adapted to mass production because of its use of standardized components which may be pre-formed. The various components of a foot—the toe, instep, heel, and sole may be sized and contoured in quantities. There will be but minor additional forming operations required after these various parts are assembled and fairings of desired shape applied thereto.

The subject artificial foot is very light in weight, durable, able to withstand shock and offers sufficient resistance to moisture. A fabricating technique is involved in the construction which is very unlike conventional techniques and which readily lends itself to mass production with consequent lower unit costs.

While certain preferred embodiments of the invention have been specifically disclosed, it is understood that the invention is not limited thereto, as many variations will be readily apparent to those skilled in the art and the invention is to be given its broadest possible interpretation within the terms of the following claims.

We claim:

1. An artificial foot comprising a primary weight bearing portion and a toe portion, said primary weight bearing portion comprising an elongated core section and a fairing element applied at each elongated side of said core section, said fairings simulating contours of the human foot, said core section and said fairing elements being comprised of balsa wood, and a protective coating formed of a shock resisting material disposed upon the exterior of the assembled core and fairings.
2. An artificial foot comprising a primary weight bearing portion and a toe portion, said primary weight bearing portion comprising a core section formed of a plurality of blocks of balsa wood with the blocks so arranged with respect to one another that the principal applied loads will be parallel to the grain of the wood, and a fairing element applied at each side of said core section, said fairings simulating contours of the human foot, and a protective coating formed of a shock resisting material disposed upon the exterior of the assembled core and fairings.
3. An artificial foot comprising a primary weight bearing portion and a toe portion movably connected thereto, said primary weight bearing portion comprising a core section formed of a plurality of blocks of balsa wood with the blocks so arranged with respect to one another that the principal applied loads will be parallel to the grain of the wood, and a fairing element applied at each side of said core section, said fairings simulating contours of the human foot, said toe portion and said fairings also comprising balsa wood, a protective coating formed of a shock resisting material disposed upon the exterior of the assembled core and fairings, and

a similar protective coating encasing said toe portion.

4. An artificial foot comprising a primary weight bearing portion and a toe portion, said primary weight bearing portion comprising an elongated core section formed of an instep section, a heel section and a sole section and a fairing element applied at each elongated side of said core section, said fairings simulating contours of the human foot, said core section and said fairing elements being comprised of balsa wood, and a protective coating formed of a shock resisting material disposed upon the exterior of the assembled core and fairings.

5. An artificial foot comprising a primary weight bearing portion and a toe portion movably attached thereto, said primary weight bearing portion comprising an elongated core section formed of an instep section, a heel section and a sole section, all suitably joined together, and a fairing element applied at each elongated side of said core section, said fairings simulating contours of the human foot, said core section, fairing elements and said toe portion being comprised of balsa wood, a protective coating formed of a shock resisting material disposed upon the exterior of the assembled core and fairings, and a similar protective coating encasing said toe portion.

6. An artificial foot comprising a primary weight bearing portion and a toe portion, said primary weight bearing portion comprising an elongated core section formed of an instep section, a heel section and a sole section, all suitably joined together, and a fairing element applied at each elongated side of said core section, said fairings simulating contours of the human foot, said core section, fairing elements and said toe portion being comprised of balsa wood, a flat hinge member of extended length for rotatively connecting said toe portion to said primary weight bearing portion, said hinge member being secured to the bottom surfaces of both said toe portion and said primary weight bearing portion and serving to strengthen the same to prevent failure in horizontal shear, a protective coating formed of a shock resisting material disposed upon the exterior of the assembled core and fairings, and a similar protective coating encasing said toe portion.

7. An artificial foot comprising a primary weight bearing portion and a toe portion movably connected thereto, said primary weight bearing portion comprising a core section having as components, an instep section, a heel section and a sole section each formed of balsa wood and so arranged with respect to one another that the principal applied loads will be parallel to the grain of the wood comprising the various sections, and a fairing element applied at each side of said core section, said fairings simulating contours of the human foot, said toe portion and said fairing elements being also comprised of balsa wood, a protective coating formed of a shock resisting material disposed upon the exterior of the assembled core and fairings, and a similar protective coating encasing said toe portion.

8. An artificial foot comprising a primary weight bearing portion and a toe portion movably connected thereto, said primary weight bearing portion comprising a core section and a fairing element applied at each side of said core section, said fairings simulating contours of the human foot, said toe portion comprising a central core and a fairing secured to each side there-

of, said primary weight bearing portion and said toe portion being comprised of balsa wood, a protective coating formed of a shock resisting material disposed upon the exterior of said weight bearing portion, and a similar protective coating encasing said toe portion.

9. An artificial foot comprising a primary weight bearing portion and a toe portion having a movable connection therewith, said primary weight bearing portion comprising a core section formed of a plurality of blocks of balsa wood with the blocks so arranged with respect to one another that the principal applied loads will be parallel to the grain of the wood, and a fairing element of balsa wood applied at each side of said core section, said fairings simulating contours of the human foot, said toe portion comprising a central core and a fairing secured to each side thereof, with said central core and fairings being comprised of balsa wood, and a protective coating formed of a shock resisting material disposed upon the exterior of said weight bearing portion, and a similar protective coating encasing said toe portion.

10. An artificial foot comprising a primary weight bearing portion and a toe portion having a movable connection therewith, said primary weight bearing portion comprising a core section having as components, an instep section, a heel section and a sole section, each formed of balsa wood and so arranged with respect to one another that the principal applied loads will be parallel to the grain of the wood comprising the various sections, and a fairing element of balsa wood

30 applied at each side of said core section, said fairings simulating contours of the human foot, said toe portion comprising a central core and a fairing secured to each side thereof, with said central core and fairings being comprised of balsa wood, a protective coating formed of a shock resisting material disposed upon the exterior of said weight bearing portion, and a similar protective coating encasing said toe portion.

35 11. An artificial foot comprising a primary weight bearing portion and a toe portion, said primary weight bearing portion comprising a core section formed of a plurality of blocks of balsa wood with the blocks so arranged with respect to one another that the principal applied loads will be parallel to the grain of the wood, and a fairing element of balsa wood applied at each side of said core section, said fairings simulating contours of the human foot, said toe portion comprising a central core and a fairing secured to each side thereof, with said central core and fairings being comprised of balsa wood, a protective coating formed of a shock resisting material disposed upon the exterior of said weight bearing portion, and a similar protective coating encasing said toe portion.

40 12. An artificial foot comprising a primary weight bearing portion and a toe portion, said primary weight bearing portion comprising a core section having as components, an instep section, a heel section and a sole section, each formed of balsa wood and so arranged with respect to one another that the principal applied loads will be parallel to the grain of the wood, and a fairing element of balsa wood applied at each side of said core section, said fairings simulating contours of the human foot, layers

45 of a strength providing material disposed between said fairings and between said various blocks of balsa wood where they engage one another, said layers serving also to bond said fairings to said core, and to bond said blocks to one another at their engaging portions, and a protective coating formed of a shock resisting material disposed upon the exterior of said weight bearing portion.

50 13. An artificial foot comprising a primary weight bearing portion and a toe portion having a movable connection therewith, said primary weight bearing portion comprising a core section having as components, an instep section, a heel section and a sole section, each formed of balsa wood and so arranged with respect to one another that the principal applied loads will be parallel to the grain of the wood comprising the various sections, and a fairing element of balsa wood applied at each side of said core section, layers of strength providing material disposed

between said fairings and said core and between said instep and heel sections and said sole section, which layers serve to bond said fairings to said core, and to bond said instep and said heel sections to said sole section, said toe portion comprising a central core and a fairing secured to each side thereof, with said central core and fairings being comprised of balsa wood, layers of strength providing material disposed between said fairings and said central core, said layers serving to bond said fairings to said central core, a protective coating formed of strength providing material disposed upon the exterior of said weight bearing portion to effect a shock resisting covering therefor, and a similar protective coating encasing said toe portion.

13. An artificial foot adapted to be operatively connected to an artificial shank, and comprising a primary weight bearing portion and a toe portion, said primary weight bearing portion comprising a core section having as components, an instep section, a heel section and a sole section, each formed of balsa wood and so arranged with respect to one another that the principal applied loads will be parallel to the grain of the wood comprising the various sections, and a fairing element of balsa wood applied at each side of said core sections, said fairing elements simulating contours of the human foot, said instep section, said heel section and said side fairings being arranged relative to one another and co-operating with one another to provide four walls which define a cavity in said primary weight bearing portion, which cavity is adapted to receive means for connecting said artificial foot to an artificial shank, and a protective coating formed of a shock resisting material disposed upon the exterior of said weight bearing portion.

14. An artificial foot comprising a primary weight bearing portion and a toe portion, said primary weight bearing portion comprising an elongated core section and a fairing element applied at each elongated side of said core section, said fairings simulating contours of the human foot, said core section and said fairing elements being comprised of balsa wood, means for rotatively connecting said toe portion to said primary weight bearing portion, means for determining the amount of movement of said toe portion relative to said primary weight bearing portion, and a protective coating formed of a shock resisting material disposed upon the exterior of the assembled core and fairings.

15. An artificial foot comprising a primary weight bearing portion and a toe portion, said primary weight bearing portion comprising a core section formed of a plurality of blocks of balsa wood with the blocks so arranged with respect to one another that the principal applied loads will be parallel to the grain of the wood, and a fairing element applied at each side of said core sections, said fairings simulating contours of the human foot, means for rotatively connecting said toe portion to said primary weight bearing portion, stop means for determining the amount of rotative movement of said toe portion toward said primary weight bearing portion, and a restraining means for determining the amount of rotative movement of said toe portion in the opposite direction, a protective coating formed of a shock resisting material disposed upon the exterior of the assembled core and fairings, and a similar protective coating encasing said toe portion.

16. An artificial foot comprising a primary weight bearing portion and a toe portion having a movable connection therewith, said primary weight bearing portion comprising a core section having as components, an instep section, a heel section and a sole section, each formed of balsa wood and so arranged with respect to one another that the principal applied loads will be parallel to the grain of the wood comprising the various sections, and a fairing element of balsa wood applied at each side of said core section, said fairing elements simulating contours of the human foot, said toe portion comprising a central core and a fairing secured to each side thereof, with said central core and fairings being comprised of balsa wood, means for rotatively connecting said toe portion to said primary weight bearing portion, stop means for determining the amount of rotative movement of said toe portion toward said primary weight bearing portion, and a restraining means for determining the amount of rotative movement of said toe portion in the opposite direction, a protective coating formed of a shock resisting material disposed upon the exterior of said weight bearing portion, and a similar protective coating encasing said toe portion.

17. An artificial foot comprising a primary weight bearing portion and a toe portion, said primary weight bearing portion comprising a core section having as components, an instep section, a heel section and a sole section, each formed of balsa wood and so arranged with respect to one another that the principal applied loads will be parallel to the grain of the wood comprising the various sections, and a fairing element of balsa wood applied at each side of said core section, said fairing elements simulating contours of the human foot, layers of strength providing material disposed between said fairings and said core and between said instep and said heel sections and said sole section, which layers serve to bond said fairings to said core, and to bond said instep and said heel sections to said sole section, said toe portion comprising a central core and a fairing secured to each side thereof, with said central core and fairings being comprised of balsa wood, layers of strength providing material disposed between said fairings and said central core, said layers serving to bond said fairings to said central core, means for rotatively connecting said toe portion to said primary weight bearing portion, stop means for determining the amount of rotative movement of said toe portion toward said primary weight bearing portion, and a restraining means for determining the amount of rotative movement of said toe portion in the opposite direction, a protective coating formed of strength providing material disposed upon the exterior of said weight bearing portion to effect a shock resisting covering therefor, and a similar protective coating encasing said toe portion.
